UNITED STATES PATENT OFFICE.

WILLIAM F. SCHACHT, OF HUNTINGTON, INDIANA.

MILK-BOTTLE STOPPER.

1,320,277.

Specification of Letters Patent. Patented Oct. 28, 1919.

Application filed June 16, 1919. Serial No. 304,505.

To all whom it may concern:

Be it known that I, WILLIAM F. SCHACHT, a citizen of the United States, residing at Huntington, in the county of Huntington 5 and State of Indiana, have invented certain new and useful Improvements in Milk-Bottle Stoppers; and I hereby declare that the following is a full, clear, and exact description thereof, reference being had to the 10 accompanying drawings, which form part of this specification.

This invention is an improvement in milk bottle stopples, and provides a novel stopple intended for use primarily by housekeepers 15 and vendors of milk to protect the milk remaining in a bottle after it has been partially emptied.

The novel stopple is made in one piece, having a convex top and a convex bottom 20 and provided with a circumferential flange that projects over the top edge of the bottle, and which flange has an ear preferably at one side which may be used as a lift or detaching device, and also to hang the stopple 25 upon a nail when it is not in use.

I will explain the invention in detail with reference to the accompanying drawings, which illustrates stopples embodying the invention as defined in the claims.

30 In said drawings:

Figure 1 is a sectional view of part of a glass milk bottle with the stopple applied thereto.

Fig. 2 is a top plan view of Fig. 1.

35 Fig. 3 is an enlarged detail vertical section on line 3—3, Fig. 2.

Figs. 4 and 5 are detail plan and sectional views of a modification of the stopple ear.

40 Figs. 6 and 7 are detail top and sectional views of another modification of the stopple ear.

Figs. 8 and 9 are detail top and sectional views of another modification of the stopple ear.

45 Fig. 10 is a sectional view of the stopple on line 10—10, Fig. 2.

The stopple shown comprises a disk-like body 1 formed of rubber or similar material and substantially corresponding in exterior 50 diameter to the interior diameter of the mouth of the bottle with which it is to be used. On the under side of this disk-like portion 1 depends an annular cylindric portion 2, which is of less diameter than part 1,

and is adapted to fit closely within the 55 mouth of the bottle, as indicated in Fig. 1, and to seat upon the usual neck *b* within the mouth of the bottle. The portion of disk 1 that projects beyond the part 2 forms a 60 peripheral flange 3 which rests upon the top of the neck of the bottle, as shown, and forms a close joint therewith and protects the top of the bottle from objects falling thereon.

The bottom of the part 2 is concaved, as shown at 4, and the top of the disk or stop- 65 ple is convexed, as shown at 5.

The part 2 is made slightly larger in diameter than the diameter of the shoulder *b* of the bottle neck; consequently, when the stopple is inserted in the bottle, the part 2 forms 70 a close fit on and within such shoulder, and is slightly annularly contracted, thereby. Due to the concavity 4 of the inner or lower part of the stopple, this contraction increases the convexity 5 of the outer or upper part 75 of the stopple.

The stopple is made concave at 4 and convex at 5; in the molding this concavity and convexity are both enhanced when the stopple is applied to a bottle.

This insures a close fit of the stopple in and on the bottle and if any weight was placed upon the stopple, it will fit all the more tightly by its tendency to expand in the neck.

80 By reason of the convexed top part 5, as described, if any foreign substances drop upon the stopple when applied to the bottle they tend to roll off and pass over the edges thereof, and over the edges of the bottle, instead of collecting and settling upon the stopple.

The novel stopple is preferably provided at one side of the flange 3 with a laterally projecting ear 6 formed integral therewith; which ear may be used as a means for readily disengaging the stopple from the bottle and also as a means for suspending it from a nail or hook when not in use. In the form shown in Figs. 1 to 3, the ear 6 is provided 90 with an oblong protuberance 7 on its upper side which is perforated for the passage of a metal ring for eye 8 by which the stopple can be readily suspended from a nail or hook when detached from the bottle. Preferably, 95 in order to strengthen the ear 6, it is reinforced by linen, canvas, or other suitable material indicated at 9, which is embedded

in the stopple and ear during the molding of the stopple and vulcanized therein. Preferably the reinforce 9 extends around the opening in the ear.

5 In the form shown in Figs. 4 and 5, the ear 6 is provided with an opening in which is secured a metal eyelet 10. This ear being provided with a reinforce 9, as indicated.

10 In the form shown in Figs. 6 and 7, the ear 6 has an opening 11 surrounded by a raised annular portion 12 on the upper side of the ear, this portion 12 strengthening the ear around the opening; the ear being reinforced as indicated.

15 In the simple form shown in Figs. 8 and 9, the ear 6 has an opening or eye 11. If desired, a ring 13 may be engaged with the opening 11, as indicated in dotted lines in Fig. 9.

20 In each instance the main body of the stopple is constructed as described, the variations being in the ears, and in the provision for suspending the stopple by the ear. The reinforce enhances the durability of the ear and flange and will prevent the opening or eye tearing out when the stopple is hung on a nail or hook.

25 The principal novel features of the stopple are the peculiarly shaped concave-convex body portions 2 and 1. I preferably arrange the ear 6 at the side and radially of the stopple, as stated; but in some cases the ear could be omitted or other provision made for suspending or detaching the stopple, the 35 essential features of the body portions thereof being preserved.

30 As stated, the stopple is intended to be used to cover the milk bottle after the ordinary paper cap is removed and the bottle 40 has been partially emptied of its contents.

45 The novel stopple being made integrally out of one piece of rubber, with convex top, rounded central portion and projecting lip, all droppings and foreign materials will run off the stopple, and not adhere thereto.

50 As the part 2 fits closely on the inside of the bottle and the flange 3 covers the top edge of the bottle, dust and air are effectually excluded; the stopple affords no lodgment for germs; and makes an airtight, sanitary closure.

I claim:

55 1. An integral stopple comprising a circular disk-like upper portion adapted to cover the mouth of a bottle, and a short depending cylindric portion of much greater width than depth adapted to fit within the mouth of a milk bottle and seat upon the shoulder thereof; the stopple being concave on its under side and convex on its outer side, the outer part of the upper portion projecting beyond the depending portion as a flat peripheral flange adapted to rest on the top of the mouth of the bottle 60 and the depending portion being of slightly

greater diameter than the interior diameter of the shoulder of the bottle; whereby when the stopple is inserted in the bottle the depending portion is contracted and its concavity increased and the convexity of the top of the disk portion also increased, substantially as described.

2. An integral stopple comprising a circular disk-like upper portion adapted to cover the mouth of a bottle, and a short depending cylindric portion of much greater width than depth adapted to fit within the mouth of a milk bottle and seat upon the shoulder thereof; the cylindric portion being concave on its under side and the disk 75 convex on its top side; the outer part of the upper portion projecting beyond the depending portion as a flat peripheral flange adapted to rest on the top of the mouth of the bottle and said depending portion being of slightly greater diameter than the inner diameter of the shoulder of the bottle; whereby when the stopple is inserted in the bottle the depending portion is contracted and its concavity increased and the convexity of the top of the disk portion also increased; said disk portion having an integral laterally projecting ear extending 80 radially therefrom whereby the stopple may be readily detached from a bottle.

95 3. An integral milk bottle stopple comprising a circular disk-like upper portion adapted to cover the mouth of a bottle and convex on its top side, and a short depending cylindric portion of much greater width 100 than depth adapted to fit within the mouth of a milk bottle and seat upon the shoulder thereof, and concave on its lower side, the depending portion being of slightly greater diameter than the shoulder of the bottle, 105 and the disk portion having a radially extending reinforced ear at one side provided with means for engagement with a nail or hook, substantially as described.

110 4. A stopple formed integrally of rubber or like material and comprising a circular disk-like upper portion adapted to cover the mouth of a bottle, and a short depending cylindric portion of much greater width than length adapted to fit within the mouth 115 of a milk bottle and seat upon the shoulder therein and of slightly greater diameter than the shoulder of the bottle; the disk portion being of slightly greater diameter than the exterior portion of the mouth of the bottle, whereby when the stopple is inserted in the bottle the depending portion is contracted; said disk portion having a radially extending ear on one side provided with an internal reinforcement and having a 120 thickened perforated portion, substantially as described.

125 5. A stopple formed integrally of rubber or like material and comprising a circular disk-like upper portion convex on its top 130

adapted to cover the mouth of a bottle; and a short depending cylindric portion of much greater width than length adapted to fit within the mouth of a milk bottle and 5 seat upon the shoulder therein of slightly greater diameter than the shoulder of the bottle; whereby when the stopple is inserted in the bottle the depending portion is contracted and its concavity increased and

the convexity of the top of the disk portion 10 also increased; said disk portion having a radially extending ear on one side provided with an internal reinforcement and having a thickened perforated portion, substantially as described.

15

In testimony that I claim the foregoing as my own, I affix my signature.

WILLIAM F. SCHACHT.
